UNITED STATES PATENT OFFICE.

LORN CAMPBELL, SR., OF MINNEAPOLIS, MINNESOTA.

DESIGN FOR A WRENCH.

57,113.

Specification for Design.

Patented Feb. 22, 1921.

Application filed October 8, 1920. Serial No. 415,707. Term of patent 3½ years.

To all whom it may concern:

Be it known that I, LORN CAMPBELL, Sr., a citizen of the United States, residing at Minneapolis, in the county of Hennepin and State of Minnesota, have invented a new, original, and ornamental Design for Wrenches, of which the following is a specification, reference being had to the accompanying drawing, forming part thereof.

Figure 1 is a perspective face view of a wrench, showing my new design; and Fig. 2 is a perspective back view of the same.

I claim:

The ornamental design for a wrench, as shown.

LORN CAMPBELL, SR.
